UNITED STATES PATENT OFFICE

152,067

DESIGN FOR A POWER WINCH

John C. Curtis, Claremont, N. H., assignor to Joy
 Manufacturing Company, a corporation of Pennsylvania

Application July 16, 1946, Serial No. 131,635

Term of patent 14 years

(Cl. D41—1)

To all whom it may concern:

Be it known that I, John C. Curtis, a citizen of the United States, residing at Claremont, in the county of Sullivan and State of New Hampshire, have invented a new, original, and ornamental Design for a Power Winch, of which the following is a specification, reference being had to the accompanying drawing, forming a part hereof, whereof

Fig. 1 is a rear perspective view of the power winch looking toward the motor-end of the winch, showing my new design;

Fig. 2 is a front perspective view of the power winch shown in Fig. 1, looking toward the motor-end of the winch;

Fig. 3 is a front perspective view of the front side of the power winch, looking toward the drum-end of the winch.

I claim:

The ornamental design for a power winch, substantially as shown.

JOHN C. CURTIS.
